CLAIM

The ornamental design for a video camera, as shown and described.

DESCRIPTION

FIG. 1 is a front perspective view of a video camera showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The even broken lines shown in the drawings are included for the purpose of illustrating portions of the video camera that form no part of the claimed design.

1 Claim, 7 Drawing Sheets
